UNITED STATES PATENT OFFICE.

ALBERT VERBER, OF NEW YORK, N. Y.

DESIGN FOR A RING.

Application filed May 5, 1922. Serial No. 2,091. Term of patent 7 years.

To all whom it may concern:

Be it known that I, ALBERT VERBER, a citizen of the United States, and residing at New York, in the county of Bronx and State of New York, have invented a new, original, and ornamental Design for Rings, of which the following is a specification, reference being had to the accompanying drawing, forming part thereof.

Fig. 1 is a top plan view of a ring showing my new design;

Fig. 2 an edge view thereof;
Fig. 3 a side view thereof; and,
Fig. 4 an edge view opposite to that illustrated in Fig. 2.

I claim:—
The ornamental design for a ring, as shown.

ALBERT VERBER.
